Primary Examiner — Catherine A Tuttle(74) *Attorney, Agent, or Firm* — Polsinelli PC(57) **CLAIM**

The ornamental design for a handheld touch object, as shown and described.

DESCRIPTION

FIG. 1 is a top, front and left perspective view showing our new design for the handheld touch object.

FIG. 2 is a front view thereof.

FIG. 3 is a back view thereof.

FIG. 4 is a top view thereof.

FIG. 5 is a bottom view thereof.

FIG. 6 is a right side view thereof; and,

FIG. 7 is a left side view thereof.

The dashed lines represent features of the handheld touch object that form no part of the claimed design.
